UNITED STATES PATENT OFFICE.

ADOLPH G. KUPETZ, OF NEW YORK, N. Y., ASSIGNEE TO UNDERWOOD ELLIOTT FISHER COMPANY, OF NEW YORK, N. Y., A CORPORATION OF DELAWARE.

TYPEWRITING MACHINE.

Application filed August 25, 1925. Serial No. 52,271.

This invention relates to line-spacing mechanism for typewriting machines, and has particular reference to the provision of the prevention of overthrow of the platen.

The line-spacing mechanism in standard Underwood typewriting machines includes a ratchet rotatable with the platen and operated by a pawl pivoted upon a slide on the platen-frame. The slide is actuated by a line-space lever, and is limited in its line-spacing movement by the engagement of the pawl with an overthrow-prevention stop. Such devices are subjected to rather hard usage, particularly in that type of machine in which the carriage-return and the line-spacing of the platen are accomplished by the use of an electric motor. Excessive strain on the over throw-prevention stop soon renders the stop ineffective to accurately determine a line-space distance, and thereafter causes the platen to overthrow its normal line-space stop position.

The present invention aims to relieve all strain, incident to a violent movement of the line-spacing lever, from the line-space pawl and the line-space wheel. This is done by providing that the line-space slide may be arrested at the end of a line-spacing stroke through abutment with the carriage-frame, while a second or auxiliary stop becomes operative independently of the first stop, to prevent overthrow of the platen beyond the line-spaced position determined by the slide. Hence the stress developed through the coaction of the line-space pawl and line-space wheel is due to the momentum of the line-spaced platen, and not from the violent manipulation of the line-space lever and the momentum of the hand and arm of the operator, or of other driving means.

These objects are accomplished by the provision of a permanent stop mounted on the platen-frame and engageable by the line-space slide, whereby movement of the slide will be arrested at the end of its line-spacing movement and without conveying any stress to the overthrow-prevention stop. In this manner, the overthrow-prevention stop is relieved of the shock incident to a sudden or violent manipulation of the line-spacing lever.

Other features and advantages will hereinafter appear.

In the accompanying drawings,

Figure 1 is a fragmentary end elevation

of a typewriting machine embodying the invention.

Figure 2 is a fragmentary front elevation with parts in section.

Figure 3 is a detail front elevation of one end of the platen-frame.

Figure 4 is a sectional view on the line 4—4 of Figure 2.

Figure 5 is a view similar to Figure 1, showing the line-space slide moved inwardly to the limit of its possible movement.

Figure 6 is a fragmentary top plan view of the device.

A platen 10 is fixed upon a shaft 11 for rotation in the ends 12 of a platen-frame supported by the usual carriage 13. A transversely movable slide 14 is mounted in one end of the platen-frame, and has pivoted, as at 15, a pawl 16 which engages a ratchet 17 rotatable with the platen 10. The ratchet 17 is engaged by the usual roller detent 17^a to maintain the platen in proper spaced position when the pawl becomes disengaged from the ratchet. Carried by a rearward extension 18 of the slide 14 is a pin 19, which is loosely engaged by an arm 20 of a vertical rock-shaft 21. The shaft 21 is supported at its bottom end in a bracket 22 and connected to the usual power-driven carriage return and line-spacing mechanism, of H. L. Pitman, patented April 13, 1926, No. 1,580,326, and designated generally by the character 23. A coil spring 24 has one of its ends secured to the extension 18 of the slide 14, while its other end is attached to one of the end members of the platen-frame, whereby the slide 14 and its associated parts will maintain a normal position, as illustrated in Figure 1.

A nose member 25, carried by the pawl 16 and having an angularly-disposed rear edge 26, co-operates with an overthrow-prevention stop 27 to prevent the ratchet and platen from running beyond their proper positions after the line-space slide 14 has been shifted. The stop member 27 is placed immediately beyond the rearward limit of the edge 26, so that it will not actually be engaged except in the event that the platen and ratchet start to overthrow.

In order to limit the rearward movement of the slide 14, and thus relieve the overthrow-prevention stop of shock, incident to the line-spacing operation, the forward end of the slide is offset as at 28. A stop mem-

- ber 29 is mounted upon the carriage 13 in the path of movement of the offset 28. This stop member is here shown as being mounted with the carriage-shift lock 30, but it may, 5 of course, be attached in any other suitable manner. The forward end of the platen-frame 12 may have a suitable reinforcement as at 31 to increase the mechanical strength of these parts.
- 10 The slide 14 may be actuated by a line-spacing lever 32, which may be manually operated or otherwise, and, when the offset 28 abuts the stop member 29, further rearward movement is prevented. In the event 15 that the lever 32 is shifted violently, so that the platen 10 and ratchet 17 tend to overrun, the engaging tooth of the ratchet will, by a cam action, raise the pawl 16 about its pivot 15, whereupon the inclined edge 26 of the 20 pawl nose will contact with the overthrow-prevention stop 27 and prevent further upward movement. Because of this structure, the ratchet tooth can never pass the pawl, and overthrow of the platen is thus positively prevented.

25 It will be noted that the line-spacing mechanism may be operated by a power drive or by hand; that a violent manipulation by hand or a manipulation by power 30 creates an overthrowing effect upon the platen; that the throw of the line-space slide and pawl is arrested at the line-spaced position by a positive stop on the frame; that

the line-space pawl, per se, loses control of the platen and line-space wheel beyond the 35 line-spaced position; that the line-spaced position of the platen is maintained at the end of the line-spacing operation, by an auxiliary stop rendered operative by the momentum of the platen to arrest the overthrowing 40 movement thereof substantially at or immediately following the arrest of the line-spacing pawl; that one stop operates to relieve the line-space wheel and platen of the shock incident to arresting the line-space 45 slide; and that the other stop checks the overthrow of the platen without excessive strain upon the coacting parts.

Variations may be resorted to within the scope of the invention, and portions of the 50 improvements may be used without others.

Having thus described my invention, I claim:

55 In a typewriting machine, the combination with a rotatable platen and a line-space wheel, of a line-space slide provided with an integral stop thereon, a manually-operable line-space lever adapted to engage said stop to move said slide, said stop also serving in operated position as a limit stop for 60 said slide, a pawl pivoted on said slide and engageable with the line-space wheel to rotate the platen, and means independent of said stop to limit the rotary movement of the platen beyond the line-space position.

ADOLPH G. KUPETZ.
